UNITED STATES PATENT OFFICE.

THEODORE H. SCHOEPF, OF PITTSBURGH, PENNSYLVANIA, ASSIGNOR TO WESTINGHOUSE ELECTRIC AND MANUFACTURING COMPANY, A CORPORATION OF PENNSYLVANIA.

CONTROL SYSTEM.

1,315,990.

Specification of Letters Patent. Patented Sept. 16, 1919.

Application filed May 8, 1916. Serial No. 96,140.

To all whom it may concern:

Be it known that I, THEODORE H. SCHOEPF, a citizen of the United States, and a resident of Pittsburgh, in the county of Allegheny and State of Pennsylvania, have invented a new and useful Improvement in Control Systems, of which the following is a specification.

My invention relates to control systems for electrically propelled vehicles and particularly to control systems for electrically driven motor trucks which are provided with storage batteries.

One object of my invention is to provide a control system of the above indicated character that shall insure a safe and economical operation of the motor or motors contained therein.

Another object of my invention is to provide a motor truck having a series-wound propelling motor, with means for insuring a safe operating speed of the motor in case the same be relieved of the load thereon by the release of the clutch, as when changing the transmitting gear.

More specifically, my invention consists of an electric vehicle provided with a series-wound propelling motor and a storage battery for exciting the motor and for additionally exciting the field winding in case the motor be relieved of the load thereon.

A clutch is provided for transmitting the driving effort of the motor to the vehicle wheels. A switch is disposed adjacent to the clutch and is adapted to be operated thereby. The switch connects a portion of the battery to the field windings for additionally exciting the same and thus prevent an excessive motor speed in case the clutch is released and the motor is relieved of the load thereon.

In the accompanying drawing illustrating my invention, Figure 1 is a diagrammatic view of a control system constructed in accordance with my invention, and Fig. 2 is a modified control system.

The motor truck 1 is provided with front wheels 2 (one only being shown) and driving wheels 3 (one only being shown) which are mounted on a driving axle 4. A driving shaft 5, having a clutch 6 interposed intermediate its ends, is connected to the driving axle 4 by means of bevel gears 7 and 8 which form a portion of a differential gear. A lever 9, connected to a rod 10, is adapted to control the operation of the clutch 6. In

Fig. 1, a contact segment 11, which is attached to the rod 10, is operated to engage contact terminals 12 and 13 when the clutch is released. In Fig. 2, a contact segment 17, which is attached to the rod 10, is adapted to engage contact terminals 18 and 19 when the clutch 6 is released.

Referring to Fig. 1 of the drawing, a motor 20, comprising an armature 21 and a field winding 22, is adapted to be energized by a storage battery 23 comprising a main portion 24 and an auxiliary portion 24a and to be controlled by a master controller MC. The master controller MC embodies a contact segment 25 which is adapted to engage contact fingers 26 and 27 and a contact segment 28 which is adapted to engage contact fingers 29, 30, 31, 32, 33 and 34 to short circuit resistors R1, R2, R3 and R4 when moved to positions *a*, *b*, *c*, *d* and *e*. A two-pole, double-throw switch 35, having switch blades 36, is adapted to connect contact terminals 37 and 38 and 39 and 40 to complete circuits from the storage battery 23 to the motor 20 when in the position shown. When the switch is thrown to its reverse position, the switch blades 36 connect contact terminals 38 and 43 and 40 and 44 to complete a circuit from the storage battery 23 to a charging receptacle 45.

Referring to Fig. 2 of the drawing, a motor 50 having an armature 51 and a field winding 52, is adapted to be energized by a storage battery 53 and to be governed by means of a master controller MC1. The master controller embodies a contact segment 54 which is adapted to engage contact fingers 55, 56, 57, 58, 59 and 60 to short circuit resistors R5, R6, R7 and R8 which are included in the circuit of the motor 50. A three-pole, double-throw switch 61, having blades 62, 63 and 64, is adapted to joint contact terminals 65 and 66, 67 and 68, and 69 and 70 to connect the motor 50 to the storage battery 53 when in the position shown. When the switch is moved to its reverse position, the switch blades 62 and 63 respectively join contact terminals 66 and 68 to contact terminals 71 and 72 so as to complete a circuit from the battery 53 to a charging receptacle 73.

Although the motor truck 1 is only partially illustrated, it is to be understood that the same may be provided with the usual transmission and differential gears common to motor cars. In order to simplify the

drawing, no means is shown for reversing the field winding relative to the armature winding in case it is desired to reverse the motor.

5 Considering the system illustrated in Fig. 1 to be in the position shown, the operation of the same may be as follows. In moving the master controller MC to position *a*, two circuits are completed, one circuit extending 10 from the auxiliary battery portion 24a through the field winding 22 and the second circuit extending from the complete battery 23 through the motor 20. The first circuit may be traced from one terminal of 15 the battery portion 24a through contact fingers 26 and 27, which are bridged by the controller segment 25, contact terminals 12 and 13, which are bridged by the contact segment 11, motor-field winding 22 and contact terminals 39 and 40, which are bridged 20 by the switch blade 36, to the other terminal of the battery portion 24a. The second circuit may be traced from one terminal of 25 the battery 23 through contact terminals 37 and 38, which are bridged by a switch blade 36, contact fingers 29 and 30 which are bridged by the controller segment 28, resistors R1, R2, R3 and R4, motor 20, and contact terminals 39 and 40, which are 30 bridged by a switch blade 36, to the other terminal of the battery 23. Thus, the series-wound motor 20 is connected in series with the battery 23, and the battery portion 24a is connected to additionally energize field 35 winding 22 in order to prevent an excessive speed of the motor, as the same is running without a load thereon. In moving the controller to positions *b*, *c*, *d* and *e*, the resistors R1, R2, R3 and R4 are successively 40 excluded from the motor circuit.

In case it is desired to start the motor car 1, the lever 9 is operated to throw the clutch 6 into its operative position. In moving the clutch 6 to its operative position, the 45 contact segment 11 is disengaged from the contact terminals 12 and 13 to break the circuit from the battery portion 24a through the field winding 22. If, during the operation of the motor car, the clutch be released, 50 the contact segment 11 again bridges the contact terminals 12 and 13 to again establish a circuit from the battery portion 24a through the field winding 22. Thus, an excessive speed of the motor 20, by reason of 55 the load being removed therefrom, is prevented.

In case it is desired to charge the battery 23, the switch 35 is thrown to its reverse position so that one switch blade 36 bridges 60 the contact terminals 38 and 43 and the second switch blade 36 bridges the contact terminals 40 and 44. A circuit is completed that may be traced from the charging receptacle 45 through contact terminals 40 65 and 44 which are bridged by the switch

blade 36, battery 23 and contact terminals 38 and 43, which are bridged by the switch blade 36, to the battery-charging receptacle 45.

Considering the system illustrated in Fig. 2 to be in the position shown, the operation of the same may be as follows. In moving the master controller MC1 to position *a*, a circuit is completed from the battery 53 through the motor 50, which may be traced 75 from one terminal of the battery through contact terminals 65 and 66, which are bridged by the switch blade 62, contact fingers 55 and 56, which are bridged by the controller segment 54, resistors R5, R6, R7 and R8, motor 50 and the contact terminals 67 and 68, which are bridged by the switch blade 63, to the other terminal of the battery 53. A second circuit is completed through a portion 53a of 80 the battery 53 which may be traced from the one terminal of the battery portion 53a through contact terminals 69 and 70, which are bridged by the switch blade 64, contact terminals 18 and 19, which are bridged by 85 the contact terminal 17, field winding 52 and the contact terminals 67 and 68, which are bridged by the switch blade 63, to the other terminal of the battery portion 53a. Thus, the motor 50 is energized by the complete battery 53, and the field winding 52 is 90 additionally energized by the battery portion 53a. In moving the master controller MC1 through positions *b*, *c*, *d* and *e*, the resistors R5, R6, R7 and R8 are successively excluded from the circuit of the motor 50.

In case the clutch 6 is operated in the system shown in Fig. 2, the contact segment 17 is disengaged from contact terminals 18 and 19 to break the circuit from the battery portion 53a through the field winding 52 and thus relieve the field winding of its additional excitation.

In order to recharge the battery 53, the switch 61 is closed in the reverse position 110 so that the switch blade 65 bridges the contact terminals 66 and 71, and the switch blade 63 bridges the contact terminals 68 and 72. A circuit is completed which may be traced from the battery-charging receptacle 73 through contact terminals 68 and 72, which are bridged by the switch blade 63, battery 53, and contact terminals 66 and 67, which are bridged by the switch blade 65, to the battery-charging receptacle 73.

The circuit connections, the arrangement of the apparatus and the general type of control system may, of course, be varied within the spirit and scope of my invention. I desire, therefore, that only such 125 limitations shall be imposed as are indicated in the appended claims.

I claim as my invention:

1. In a control system, the combination with a motor having armature and field 130

windings, and adapted to drive a mechanical load, a source of propulsive energy therefor, and an auxiliary source of means for increasing the excitation of the field winding relative to the armature winding from said auxiliary source in case the motor is relieved of said mechanical load.

2. In a control system, the combination with a motor having series-wound armature and field windings and adapted to drive a mechanical load and a battery for the motor comprising a main and an auxiliary source of energy, of means for connecting said auxiliary source of energy across the field winding in case the motor is relieved of said load.

3. In a control system for an electric vehicle, the combination with an electric motor having armature and field windings and adapted to drive a mechanical load, and a battery for the motor comprising a main and an auxiliary source of energy, of means for connecting said auxiliary source of energy across the motor field winding in case the motor is relieved of said load.

4. In a control system for an electric vehicle, the combination with an electric motor having series-wound armature and field windings, and adapted to drive a mechanical load, and a main storage battery for energizing the motor, of an auxiliary storage battery embodying a portion of said main battery, and means for connecting said auxiliary storage battery across said field winding in case the motor is relieved of said load.

5. In an electric vehicle, the combination with an electric motor having series-wound armature and field windings and a clutch for transmitting the driving effort of the motor to the vehicle wheels, of means operated by the clutch for controlling the excitation of the field winding.

6. In an electric vehicle, the combination with an electric motor having series-wound armature and field windings and a clutch for transmitting the driving effort of the motor to the vehicle wheels, of means for increasing the excitation of the field winding relative to the armature winding in case the clutch is released.

7. In an electric vehicle, the combination with an electric motor having series-wound armature and field windings, a storage battery comprising a main and an auxiliary source of energy for supplying energy thereto and a clutch for transmitting the driving effort of the motor to the vehicle wheels, of means controlled by the clutch for connecting the auxiliary source of energy in series with the field winding.

8. In an electric vehicle having a driving

axle, the combination with a series type motor having armature and field windings, a clutch for connecting the motor to the driving axle and a source of energy for said motor, of means for increasing the excitation of the field winding relative to the armature winding in case the clutch is released and the motor is relieved of the load thereon.

9. In an electric vehicle having a driving axle, the combination with a motor having series-wound armature and field windings and a main storage battery for supplying energy thereto, a controller for governing the operation of the motor and a clutch for connecting the motor to the driving axle, of an auxiliary storage battery embodying a portion of said main storage battery and means for connecting said auxiliary storage battery across the field winding in case the clutch is released while the controller is in an operative position.

10. In an electric vehicle, the combination with an electric motor having an armature and a series-related field winding, and means for transmitting the driving effort of the motor to the vehicle wheels, of means operated concurrently with said transmitting means for controlling the excitation of said field winding.

11. In an electric vehicle, the combination with an electric motor having an armature and a series-related field winding, and means for transmitting the driving effort of the motor to the vehicle wheels, of means dependent upon the position of said transmitting means for increasing the excitation of the field winding relative to the armature winding.

12. In an electric vehicle, the combination with a main and an auxiliary source of energy, an electric motor having an armature and a field winding, and means for transmitting the driving effort of the motor to the vehicle wheels, of means for operating said transmitting means and for connecting said auxiliary source in circuit with the field winding.

13. In an electric vehicle, the combination with a main and an auxiliary source of energy, an electric motor having an armature and a field winding, and means for transmitting the driving effort of the motor to the vehicle wheels, of means active when said transmitting means occupies an inoperative position for increasing the excitation of the field winding from said auxiliary source.

In testimony whereof I have hereunto subscribed my name this 24th day of April, 1916.

THEODORE H. SCHOEPP.
